UNITED STATES PATENT OFFICE.

DANIEL V. MOTT, OF FERNIE, BRITISH COLUMBIA, CANADA, ASSIGNOR TO EDWARD G. DANIELS, OF FERNIE, BRITISH COLUMBIA, CANADA.

RAIL SECURING AND SUPPORTING MEANS.

1,354,000.

Specification of Letters Patent. Patented Sept. 28, 1920.

Application filed June 17, 1919. Serial No. 304,972.

To all whom it may concern:

Be it known that I, DANIEL V. MOTT, a citizen of the United States, residing at Fernie, in the Province of British Columbia, 5 Dominion of Canada, have invented certain new and useful Improvements in Rail Securing and Supporting Means; and I do hereby declare the following to be a full, clear, and exact description of the invention, 10 such as will enable others skilled in the art to which it appertains to make and use the same.

This invention relates to rail supporting and securing means, and more particularly 15 to means for supporting and securing the rails of a railroad.

One of the main objects of the invention is to provide comparatively simple, but 20 strong and durable and highly efficient means whereby the rails of a railway may be readily secured and supported in proper relation.

A further object is to provide rail supporting means which may be quickly and easily 25 laid thus permitting a railway to be constructed much more quickly than is possible by the present method of employing cross-ties for supporting the rails.

A further object is to provide rail supporting members which may be readily 30 formed by bending or rolling from sheets of metal of suitable gage, these members extending the full length of the rails so as to effectively brace the same.

35 Further objects will appear from the detailed description.

In the drawings:

Figure 1 is a fragmentary top plan view 40 of a railway employing rail securing and supporting means constructed in accordance with my invention.

Fig. 2 is a section taken substantially on line 2—2 of Fig. 1.

Fig. 3 is a detail fragmentary sectional view taken through the rail supporting member and associated parts.

Fig. 4 is a similar view of a modified form.

Fig. 5 is a section taken substantially on line 5—5 of Fig. 3.

Fig. 6 is a fragmentary vertical section through another modified form of rail supporting member and associated parts.

In practice, I provide a substantially T-shaped rail supporting member designated

generally by 1 which extends the full length of each rail A. This supporting member is formed from a sheet or plate of metal, preferably steel, of suitable gage which is formed by bending or rolling to provide a central 60 stem 2 formed of the two parallel closely adjacent arms 3. The material of the supporting member at the upper end of each arm is turned outwardly at right angles to provide a horizontally disposed supporting plate 4, 65 these plates forming a seat for the base flange 5 of the rail. A suitably shaped anchor plate 6 is mounted upon the outer supporting plate 4 and is secured thereto by bolts 7, or suitable equivalent securing 70 means. This anchor plate also, preferably, extends the full length of the rail.

The inner arms 4 of the supporting members 1 are connected by suitable tie plates 8, the end portions of which are positioned beneath the arms. This tie plate is provided, at each end, with a thickened portion 8^a which is suitably bored and threaded to receive a securing bolt 9 inserted through an inner anchor plate 10 which is provided with 80 an inner offset extension 11 secured by rivets 12 or equivalent means to tie plate 8. The inner and outer anchor plates coat in the well known manner to secure the rails A in proper position upon the supporting 85 member 1, and the tie plates 8 serve to positively maintain these rails in proper relation. As will be noted, the central plane of the stem 2 of supporting member 1 is coincident with the central plane of rail A thus 90 effectually preventing all rocking or side play of the rail.

In practice, the supporting members 1 are placed in parallel spaced relation with the stem portions thereof firmly embedded in the 95 road bed. The rails, consisting of sections, are then placed upon the supporting plates 4 of members 1 and moved into proper position to have their base flanges extended beneath the outer anchor plate 6, after which the tie plates 8 are placed in position by having their end portions inserted beneath the inner supporting plates 4 so as to bring the inner anchor plate 10 into proper relation with the inner portion of the base flange 105 of the rail, after which the securing bolts 9 are tightly secured in position, all bolts and other securing members being tightened up to prevent looseness or play. As will be noted, the securing bolts 9, in addition to 110

passing through the inner anchor plates, are also passed through openings in the inner supporting arms 4 thus serving to positively secure the supporting members together 5 while also securing the anchor plates in operative position. It is possible, by employing the substantially T-shaped supporting members in the manner stated, to lay a railway very quickly thus effecting a material saving in cost of labor over the present 10 method employing crossties of wood. Also, it is to be noted that the rails are supported throughout their whole length so as to be effectively braced and held against pounding or play.

In the modified form of supporting member illustrated in Fig. 4, the outer anchor plate 6 is replaced by a plate 13 integral with the outer arm 4 of member 1, this 20 plate 13 being formed by extending the supporting plate or arm 4 and then folding the same downwardly and inwardly upon itself as illustrated, the plate 13 being provided at its inner edge with an integral element 14 adapted to engage about the base flange 5 of the rail.

In the modified form illustrated in Fig. 6, the inner supporting plate 4 is elongated and folded upwardly and inwardly upon 30 itself to provide an upper supplemental supporting plate 15 which bridges the space between the upper ends of the two arms 3 of stem 2, the outer edge of this plate 15 fitting snugly against the element 14 at the 35 base thereof. In this form, an inner anchor plate 16 which corresponds to the inner anchor plate 10 is secured to the inner arm 4 and tie plate 8 and cooperates with element 14 to secure the base flange 5 of the 40 rail in the manner previously described. The supplemental supporting plate 15 provides a flat base which extends the full 45 width of the base flange of the rail and serves to reinforce and brace the supporting member 1 thus permitting this member to be made of relatively light material. This form of supporting member is intended more particularly for use in connection with mine and narrow gage railways in 50 which the load is not excessively heavy.

It will be evident that there may be slight changes made in the construction and arrangement of the details of my invention without departing from the field and scope 55 of the same, and I intend to include all such variations, as fall within the scope of the

appended claims, in this application in which a preferred form only of my invention is disclosed.

What I claim is:

1. In rail securing and supporting means, supporting members of substantially T-shape in cross section, anchor plates mounted on the outer arms of the heads of said T-members, tie rods having their end portions inserted beneath the inner arms of the heads of the T-members, inner anchor plates carried by said tie rods and adapted to fit over the inner arms of the T-members, and means for securing the inner anchor plates to said inner arms, said means also serving to secure the tie rods to the inner arms so as to hold the supporting members in predetermined spaced relation. 60

2. In rail supporting and securing means, a supporting member of substantially T-shape in cross section, one of the arms of the head of said member being folded upwardly and inwardly upon itself to provide a supplemental supporting element adapted 80 to extend beneath the base flange of a rail, and means for securing the rail in place. 75

3. In rail supporting and securing means, a supporting member of substantially T-shape in cross section, one of the arms of the head of said member being turned upwardly and inwardly to provide a supplemental supporting plate extending across the upper end of the stem of said member and disposed in superposed relation to the head 85 thereof for receiving and supporting the base of a rail. 90

4. In rail supporting and securing means, a supporting member formed from a sheet of material bent to provide a stem and outwardly directed supporting arms extending substantially at right angles from the upper end of said stem at each side thereof, one of said arms being folded upwardly and inwardly upon itself and provided with a rail base engaging element at its inner edge and the other said arm being folded upwardly and inwardly upon itself and extended across the upper end of the T so as to brace the same and provide a supporting 105 plate for the base of a rail mounted thereon. 95

In testimony whereof I affix my signature in presence of two witnesses.

DANIEL V. MOTT.
